UNITED STATES PATENT OFFICE

EDWARD A. BUCKMAN, OF LOS ANGELES, CALIFORNIA

COMBINATION SINK AND GARBAGE-DISPOSAL MEANS

Application filed June 9, 1928. Serial No. 284,069.

This invention relates to and has for a principal object the provision of an improved type of sink and garbage disposal means including an adjustable connection between the sink and the usual drain to the sewer whereby liquid contents of the sink and garbage may be selectively discharged from the sink into the drain pipe and a garbage receptacle disposed below the sink, respectively.

10 Another object is to provide a connection between the sink and the trap which is usually connected with the drain to the sewer, together with manually operable means for moving said connection so that garbage deposited in the sink may be discharged therefrom into a garbage receptacle positioned below the sink.

15 Other and more detailed objects of invention will appear as the description progresses.

20 In the accompanying drawings I have shown a preferred form of device subject to modification within the scope of the appended claims, without departing from the spirit thereof. In said drawings,

25 Fig. 1 is a plan view of my improved sink and garbage disposal means as seen from the plane of line 1—1 of Fig. 2.

Fig. 2 is a sectional elevation of the same on line 2—2 of Fig. 1.

30 Fig. 3 is a sectional elevation of the same on line 3—3 of Fig. 1.

Fig. 4 is an enlarged fragmentary section of the lower portion of the structure shown in Fig. 2, on line 4—4 of Fig. 3.

35 Fig. 5 is an enlarged fragmentary view of the adjustable connection between the sink and the drain pipe, as seen on line 5—5 of Fig. 1.

40 Fig. 6 is an external view of the door in the wall for closing the compartment in which the garbage is collected and through which the garbage receptacle may be inserted in and removed from said compartment.

45 Fig. 7 is a sectional plan on line 7—7 of Fig. 5.

Fig. 8 is a sectional plan on line 8—8 of Fig. 5.

50 The structure embodied in my invention includes the usual sink basin S attached to a wall W of a building and mounted above a

compartment A which is formed within a metal or wooden enclosure a extending from the floor F to the bottom of the sink S. The compartment A is open on the outside of the wall W so as to afford access thereto and said compartment may be closed by means of a door a'.

55 A garbage receptacle B is adapted to be supported in the compartment A below an opening S' in the bottom of the sink. Said opening is of substantial area and is preferably elongated so that garbage deposited in the sink S may be discharged through the opening S' into the receptacle B.

60 Instead of the permanent connection usually provided between the sink S and the drain pipe D, I provide a movable fitting D' of L-shape which has an enlarged inlet D' at its upper end conforming to the shape of and adapted to fit over the opening S' in the sink. The inlet d is preferably covered with a perforated plate or grate, as at d', which permits the liquid contents of the sink S to drain therethrough into the drain pipe D, but prevents garbage or any other solid contents of the sink to enter said drain pipe.

65 The drain pipe D is provided with a collar 1 on the upper end thereof, as shown in Fig. 3, which has a continuing and upwardly extending sleeve 2 fitted thereinto. The fitting D' has a downwardly extended nipple 3 with a flange 4 thereon slightly below the horizontal portion d. The nipple 3 is slidably and rotatably mounted within the sleeve 2 and a collar 5 is rotatably held thereon between the flange 4 and the upper end of the sleeve 2.

70 The flange 4 has a pair or more of radially formed notches 6 therein, while the collar 5 has a corresponding number of correspondingly formed ribs 7 adapted to be moved in and out of registration with said notches for rendering the fitting D' operative or inoperative, as the case may be, for directing liquids from the sink to the drain pipe. The collar 5 has a handle H attached thereto and extended radially therefrom, as shown in Figs. 1 and 5 so that when the ribs 7 on collar 5 engage the flat lower edge of the flange 4 the mouth d of fitting D' will be held in snug engagement with the outlet S' of the sink so that liq-

100

uids may flow from the sink through the fitting and into the drain pipe D.

The movement of the handle H in a counter-clockwise direction, as shown in Figs. 1 5 and 5, will move the ribs 7 and collar 5 into registration and engagement with the notches 6 on flange 4, thus permitting the dropping of the fitting D' downwardly from engagement with the sink. The further movement 10 of the handle H, due to the inter-meshing of the collar 5 and flange 4 of fitting D', will effect a rotary movement of the fitting D' outwardly from beneath the outlet S' of the sink so that garbage may be deposited in the re- 15 ceptacle B through the outlet S'. The movement of the handle H in a reversed direction will effect the movement of the fitting D' into a position below the outlet S', while the further movement of the handle will serve to elevate 20 the fitting into operative engagement with the outlet.

Suitable means may be provided for limiting the movement of the member D' and for guiding the fitting in its upward movement 25 such as is shown in Fig. 5 at 8 and 9. Said members 8 and 9 depend from the sink S and the member 8 is preferably longer than the member 9 so that in moving the fitting D' into operative position the member 8 will serve 30 to limit such movement, and together with member 9 will act as a guide while the member D' is being elevated to operative position.

In operation, the sink may be readily connected with or disconnected from the drain 35 D so that garbage or other solid contents of the sink S may be discharged into the garbage receptacle. In a like manner, the sink may be readily connected with the drain so that the liquid contents thereof may be drained 40 to the sewer as in other types of sinks.

The garbage compartment A, being closed from the room in which the sink is located and easily accessible from outside the building, is conveniently located and may be of substantial size. The compartment A may be provided with a vent 10 within the wall W and may be further connected by means of a horizontal passage 11 beneath the floor F with the exterior of the building. To this end an 50 aperture 12 is provided at the outer end of passage 11, while an aperture 13 is provided in the floor for affording communication between the passage 11 and the compartment A. Preferably the connection between the drain 55 pipe D and the fitting D' is enclosed by means of a metal or wooden casing, as at 14, which extends from one side of the wall a of the compartment A.

Having thus described my invention, what 60 I claim is:

1. A device of the character described comprising a sink having an outlet, a drain pipe arranged for connection with said sink, and a fitting adjustable vertically and later- 65 ally on said drain pipe relative to said outlet

and means for adjusting said fitting into and from operative connection with said outlet, for the purpose described.

2. A device of the character described comprising a sink, a garbage enclosure secured to the sink and arranged to hold a garbage receptacle, said sink having an outlet, a drain pipe, and a fitting movably supported on said drain pipe relative to and adapted to be moved selectively into and from operative connection with said outlet, whereby the liquid and solid contents of the sink may be respectively discharged into the drain pipe and the garbage receptacle. 70 75

3. A device of the character described comprising a sink having an outlet, a housing formed below said sink, a garbage receptacle in said housing, a drain pipe, and a fitting rotatably connected with said drain pipe and arranged for movement into and from operative connection with said outlet, for draining the liquid and solid contents of the sink selectively into said drain pipe and said garbage receptacle. 80 85

4. A device of the character described comprising a sink having an outlet, a drain pipe, a fitting rotatably mounted on said drain pipe, and having an inlet adapted for operative and inoperative connection with said outlet, and means extended from said fitting for adjusting the position of said fitting for the purpose described. 90 95

5. A device of the character described comprising a sink having an outlet, a drain pipe, a fitting having a mouth arranged for connection with said outlet and a nipple arranged for rotatable connection with said drain pipe, and co-operating means on said drain pipe and said fitting for reciprocably and rotatably moving said fitting to and from operative connection with said outlet. 100 105

6. A device of the character described comprising a sink having an outlet, a drain pipe, a fitting having a mouth arranged for connection with said outlet and a nipple arranged for rotatable connection with said drain pipe, co-operating means on said drain pipe and said fitting for reciprocably and rotatably moving said fitting to and from operative connection with said outlet, and means for limiting the rotary movement of said fitting and for guiding the same during the reciprocable movement thereof. 110 115

7. A device of the character described comprising a sink having an outlet, a drain pipe, a fitting having a mouth adapted to fit over said outlet and a nipple adapted to telescope into and rotate in said drain pipe, and means for initially moving said fitting downwardly and thence rotating the same in a given direction for disconnecting the sink and the drain pipe, and for rotating said fitting in a reverse direction and elevating the same for operatively connecting the drain pipe and the sink. 120 125 130

8. The combination with a sink and a drain pipe, of a fitting vertically and rotatably movable in opposite directions, for connecting and disconnecting said sink with said drain pipe.
- 5 9. The combination with a sink and a drain pipe, of a fitting vertically and rotatably movable in opposite directions, for connecting and disconnecting said sink with said drain pipe, and means for adjusting said fitting.
- 10 10. The combination with a sink and a drain pipe, of a fitting vertically and rotatably movable in opposite directions, for connecting and disconnecting said sink with said drain pipe, means for adjusting said fitting, and means for limiting the rotary movement and for guiding said fitting in its vertical movement.

20 EDWARD A. BUCKMAN.
